CENTRAL-CONTROL CONE-DRIVE MACHINE.

1,126,634.

Specification of Letters Patent.

Patented Jan. 26, 1915.

Application filed September 11, 1914. Serial No. 861,182.

To all whom it may concern:

Be it known that we, ROBERT T. HAZELTON and SOL EINSTEIN, citizens of the United States, and residing at Cincinnati, in the county of Hamilton and State of Ohio, have invented a new and Improved Central-
Control Cone-Drive Machine, of which the following specification is a full disclosure.

This invention proposes an improved machine-tool organization and it deals more especially with machines in which speed variations of the spindle are obtainable, as by means of a direct-acting cone-pulley, and in which the table or carriage is propelled 10 through a feed-change mechanism by an appropriate transmission system which initially derives motion in direct proportion to the speed of the spindle, and ultimately transmits the same through said feed-change 15 mechanism to said table or carriage. Now, this invention endeavors so to organize the above stated arrangement that the feed-change mechanism will be positioned as a unit on an appropriate frame-unit in close 20 proximity with the under surface of the table or of the element providing the table slide, and preferably below the path of travel of the table, and provided with one or more control levers mounted on that side of 25 its housing adjacent and within the immediate reach of the attendant, whereby he will be enabled to govern the rate of the feed 30 of the table without shifting his position.

Another object within the contemplation 35 of this invention is to formulate an arrangement in which the entire feed-change mechanism will be mounted on or carried by one or more of the floating frame-units, in coöperating relation with a transmission 40 that initially derives motion at a rate directly proportional to the speed of the spindle, and which transmits said motion through said feed-change mechanism to enable the table to be fed at the pre-determined rate.

Other objects will be in part obvious from the annexed drawings and in part indicated in connection therewith by the following analysis of this invention.

This invention accordingly consists in the features of construction, combination of parts and in the unique relations of the members and in the relative proportioning and disposition thereof; all as more completely outlined herein.

To enable others skilled in the art so fully to comprehend the underlying features thereof that they may embody the same by the numerous modifications in structure and relation contemplated by this invention, 60 drawings depicting a preferred form have been annexed as a part of this disclosure, and in such drawings, like characters of reference denote corresponding parts throughout all the views, of which:—

Figure 1 is a side-elevation of a milling machine of a knee-and-column cone-driven type and typifying the manner in which this invention may be embodied. Fig. 2 is a 70 diagrammatic drawing, depicting a gear arrangement such as may be used for deriving a series of feeds as well as a quick-traverse of the table; the various gears being brought into one plane to avoid the confusion incidental to an ordinary drawing. 75 Fig. 3 is a side-elevation looking to the right of Fig. 1, showing a portion of the table-feeding transmission which derives motion from the spindle; and also showing the quick-traverse pulley which in this instance derives motion from the counter-shaft 80 independently of the spindle.

To obtain an adequate understanding of this invention, it should be kept in mind that the term "feed" as used herein indicates any one of a series of relatively slow movements of the table, such as essentially are suitable for tooling operations; and the term "feed-change mechanism" or "feed changer" indicates only that particular organized gear-set which determines the rate 90 at which the table thus feeds, and is to be distinguished from such variable-speed devices as may be arranged to effect changes 95 well identified with the tooling operation, as referred to and which determines the rate of rotation of the counter-spindle.

Before detailing the specific features of construction whereby these functions are attained it will be convenient first to describe certain major elements of a conventional milling machine. These comprise a table Y that supports the work and which is reciprocated to-and-fro to subject the work bolted 100 thereon to the effect of the tool or cutter that is secured to an appropriate tool-supporting member here typified by a spindle X which, in this instance, is continuously 105 rotated by power derived from the same 110

source or prime-mover that actuates the table. In order to enable the machine properly to execute its functions, these actuated elements must be capable of being brought 5 into adjustable relation with one another in two directions. This is accomplished by an interponent frame-unit B that intervenes between the frame-unit A that directly supports the spindle or tool-supporting member 10 and the frame-unit C that directly mounts the table. In the type of machine illustrated, the interponent frame-unit B is commonly termed a "knee"; the table-supporting frame-unit C is usually termed a "saddle", and the spindle mounting frame-unit A is generally termed a "column". The chief mechanical characteristic of the interponent frame-unit B is that it provides for a relative vertical adjustment as to the spindle-mounting unit, and a horizontal adjustment as to the table-supporting unit, *i.e.*, in a direction transverse to the other.

The spindle-mounting frame-unit, or "column" A, has heretofore been that also selected to rest on the floor and thus provide a foundation for the machine, as a whole, and it has also been utilized to support or mount both the change-gear mechanism that varies the speed of the spindle, as well as the 25 change-gear mechanism that varies the rate of feed of the table. This, however, has resulted in a very considerable inconvenience to the attendant in manipulating the machine. That is to say, the attendant must be 30 stationed at the outer longitudinal side of the reciprocating table in order to scrutinize the action of the machine, but, when so stationed, he is out of reach of the levers that effect all the changes of the rate of feed of 35 the table, so that, in order to make these changes he must shift his position.

This invention proposes, among other things, a rearrangement and a reconstruction 40 of the control elements so as to free the so-called "column" of the machine from the mechanism that governs the rate at which the table shall feed, and so to locate the said mechanism, and so to combine it with other 45 control features that the attendant, when stationed at the outer longitudinal edge of the reciprocating table (the edge remote from the frame-unit that uprises across the plane of the table) and without shifting his position, will be able, first, to change the rate 50 at which the table feeds, *i.e.*, to vary its speed during a cutting-stroke; second, to change the direction of travel of the table, either manually or automatically; and third, to stop the movement of the table either 55 manually or automatically. In carrying out this aspect of this invention, one of the frame-units carrying the weight of the table may assume any conventional proportion or configuration, such as are indicated on the 60 drawings, but with this distinction, that it is

contrived also to support or carry the weight of what may be termed a "feed-change" box, *i.e.*, the casing and elements constituting a change-gear mechanism such that the rate of "feed" may be varied at will. This box may also include other control features, such as the means for determining the direction of movement of the table.

A more comprehensive grasp of the various aspects of this invention may perhaps be obtained by tracing the course of motion through the machine in connection with a description of the structural features involved.

The means for quickly translating the table during non-feeding intervals will now be described. This is a quick-traverse transmission which functions to shift the table, with as little loss of time as possible, to the station at which the actual tooling begins. Referring to Fig. 1, K denotes the pulley mounted at one side of the column A and driven independently of the spindle X by means of a belt P¹ which, in this instance, receives motion from a suitable counter-shaft. The shaft of the pulley K is journaled in a suitable bracket or housing M mounted at one side of the column A, and this pulley shaft terminates in a knuckle N which is in turn connected to an extensible shaft O, the other end of which is secured to a knuckle Q connected to the shaft 9 so that said shaft will be constantly driven at a high speed. The disk I is secured to the other end of the shaft 9 and it co-operates with an element I¹ (typifying a frictional or yielding part) which is pressed against the disk I, as by means of a part I², which is non-rotationally retained by a cup-like end of a sleeve I³ which is in turn journaled in the wall of the box mounting the transmission system so as loosely to circumscribe the end of the shaft 9. By screwing up the follower I⁴, any desired pressure may be brought to bear on the two sides of the intervening friction-element I¹ so that the sleeve I³ will be frictionally driven at a rate corresponding to the shaft 9. These parts constitute a quick-traverse transmission having an impulsive driving capacity, *i.e.*, one embodying a friction-drive so that, when the quick-traverse transmission is thrown abruptly into action, a slight slip or yield will result in the drive to relieve the inertia and save the parts from the otherwise damaging strains of an unduly abrupt action. The sleeve 10 when shifted to the left as seen by Fig. 2, will become engaged with the sleeve I³ by means of its clutch-teeth so that a driving-relation between these two parts will then exist with the result that motion will be imparted to the table at a quick-traverse rate. The motion appropriate for tooling operations is obtained by gearing down or reducing the motion of the shaft 9

through a suitable feed-change mechanism so as to obtain any desired rate of reduced travel corresponding with the tooling to be done.

- 5 The means instrumental in transmitting motion from the sleeve 10 to the table may embody a bevel gear 11, which is restrained against axial movement and meshes with a bevel 12 here shown as secured to a shaft 13, 70
 10 which in turn carries a beveled gear 14 at its upper end and which meshes both with the bevel R and the bevel L which are journaled in the table support C, here instanced as a "saddle." Passing through these bevels 15 gears R and L is a sleeve 15 which is normally in loose relation with these bevels, but which is splined to the shaft 16. In this embodiment, this shaft or feed-screw 16 is fixed against translation by means of the 75
 20 collars 17, and it is provided with screw-threads 18 meshing with a nut 19 that is non-rotatably mounted on the table Y so as to translate therewith. By this means, the table will be caused to travel at the rate 25 determined by the rotation of the screw-shaft 16.

A motion-reverser is interposed in the transmission extending from 10 to 19 and it comprises a clutch-member J which is 30
 35 splined to the sleeve 15 and carries clutch-teeth at its ends whereby it may be engaged with corresponding teeth on the beveled gears R and L, so that, when the clutch member J is shifted to the one side, the 40
 45 table will be caused to travel to the right and, when it is shifted to the other side, the table will be caused to travel to the left. When this clutch-member is shifted on the sleeve 15 to an intermediate position, no motion at all will be transmitted, and hence the table will cease to travel.

The spindle-actuating system may now be described.

At a convenient point on the column A is 45
 50 journaled a spindle X which is rotated at the desired rate of speed by power transmitted through either of the steps x , x^2 or x^3 and derived from an appropriate belt P driven in the usual manner from a counter-shaft. This constitutes a drive for the spindle 55 which embodies a speed-change mechanism as typified by the cone-pulley.

The table-feed transmission will now be detailed. In the embodiment under description, this transmission derives its motion directly from the spindle (instead of directly from a prime-mover) so as to be actuated in the first instance at a rate directly proportional to the speed of the spindle. This transmission in the form here shown includes a sprocket-wheel 1 which is 60
 65 mounted directly on the spindle, and which propels the sprocket-chain 2 which in turn rides around the sprocket-wheel 3 mounted in a lower portion of the column A as in-

dicated on Fig. 3. Secured to the sprocket-wheel 3 is a gear 4 that meshes with the gear 5 to which in turn is secured the knuckle 6. An extensible shaft 7 connects the knuckle 6 with the knuckle 8, which latter is keyed to a shaft d^3 journaled in the walls of the housing for containing the organized feed-change mechanism. In this embodiment, the sprocket-wheel 1 may be regarded as the initial terminal-member of the table-feed transmission and its ultimate terminal-member may be considered to be the sleeve 10 which is loosely mounted on the shaft 9 and is devised to be shifted thereon so as to be connected on the one hand with the quick-traverse transmission, or on the other hand with the feed-change transmission, as by means of appropriate clutch-teeth at its respective ends. This sleeve 10 may be shifted or positioned manually or automatically, as by the mechanism described fully in our co-pending application, Serial #850175, filed July 10th, 1914. The remainder of the feed motion transmission, including the gearing enabling the rate of feed to be varied, will now be described. In this embodiment, this transmission also extends from the initial terminal-member 1 to the ultimate terminal-member 10, which in this instance is shiftable. Splined to shaft d^3 are two shiftable gear-units d^4 and d^5 . The former carries the gears d^6 and gear d^7 , and the latter carries the gears d^8 and d^9 , and the purpose of enabling these gear bearers to be shifted is to utilize one or another of said four gears for propelling or transmitting purposes. Keyed to a shaft journaled in parallelism with shaft d^3 is a series of gears D^6 , D^7 , D^8 , D^9 and D^{10} which is so arranged that gear d^3 105
 110 may be brought into mesh with gear D^6 , and so on. In a suitable manner, motion is derived from one of these five gears. Thus, the gear-unit g carries a gear g^{10} which may be brought into mesh with gear D^{10} by a lateral movement of the unit g , or similarly the gear g^8 may be meshed with gear D^8 . Inasmuch as the unit g is splined to a sleeve g^1 , the latter will be rotated at a rate dependent upon the character of the foregoing 115
 120 intermeshing; with the effect that gear g^2 , which is fast to the sleeve g^1 , will directly drive the gear G^2 and indirectly the gear G^3 at a corresponding rate. The gear G^3 and the sleeve g^1 constitute terminal members, either of which may be brought into propelling relation with a gear h which is splined to and therefore drives the shaft h^1 . This connection is effected on the one hand by the clutch-teeth at the end of the 125
 130 sleeve g^1 . Fixed to the end of the shaft h^1 is a driving disk h^2 which carries a shear pin h^3 that projects into a corresponding recess in the companion disk h^4 and therefore drives the gear h^5 . The purpose of this

pin arrangement is to centralize all possibility of fracture on the pin h^s so as to cause the breakage to occur in an easily replaceable element in case of any undue load. 5 By this construction, a positive drive for all safe loads is insured during all tooling operations thereby enabling definite feeds and effects always to be secured, while yet avoiding any consequential damage to the machine in the event of excessive loads due either to accident or bad judgment on the part of the attendant. By combining this positive feed safety device with the above-described impositive quick-traverse safety means, the attendant becomes able safely to urge the machine to its utmost output from all standpoints. It should be noted that a primary characteristic of this combination is that it results in an effect unattainable by means of a single safety means of ordinary construction; that is to say, this combination affords a differential effect in that correct safety points are provided both for the relatively slow, but necessarily powerful "feed" of the table, as well as for the speedier and less resisted "quick-traverse" of the table. In accordance with this invention, the safety feed device will be so constructed as to transmit a predetermined stress such that the table will be "fed" against the resistance of safe tooling operations, and yet so as to yield or fail to transmit should an undue resistance accrue. For example, in this instance, the safety feed device will transmit the power necessary to feed the table against a resistance of from four to five tons pressure as a maximum. This will suffice for the tooling operations. The co-operating safety means, however, which exercises its office during the quick-traversing of the table is designed to yield under materially less stresses so that the table may be propelled against a resistance of only about one-fourth or one-fifth of that above-mentioned, say of one ton, since it is necessary for shock-absorbing purposes to use a comparatively free-acting yieldable friction means in handling the momentum or inertia of the parts. The gear h^s in turn permanently meshes with gear H^s which in this embodiment constitutes a terminal member of the "feed" mechanism. That is to say, the gear H^s has clutch teeth whereby it may be connected with the ultimate terminal member 10, when it is properly shifted, and thereby cause the motion to be transmitted at the appropriate feeding rate, instead of at the quick-traverse rate. Inasmuch as the members d^s and d^s enable feed-changes to be made, and the member g introduces two other multipliers in serial relation with these changes, and the member A also introduces two more multipliers in serial relation, it will therefore be evident that four times two times

two, or sixteen different changes of feed are rendered available. The means whereby the above-mentioned clutches or their shiftable elements may both be moved manually as may now briefly be explained.

Referring to Fig. 1, D indicates one of the hand-levers that extends forwardly from one side of the housing C'' for the change-gears and terminates in a hand-grasp located adjacent the front longitudinal edge of the table so as to be immediately accessible to the attendant when standing at his most effective operative station. The shank 50 of this hand-lever extends through a guide plate 51 that extends laterally from the housing C^s and it is pivoted at 59 to rock sleeve 54 that enters the gear-case and terminates in a shoe 57 whereby the gear unit d^s may be shifted laterally by swinging lever B up and down when it is in proper position. The end 52 of the lever B terminates in teeth which mesh with rock-like teeth in the plunger 61 which extends loosely through the bore of the sleeve 54. The purpose of this is to enable the plunger 61 to be moved in an axial direction by swinging the lever D in its horizontal plane. The said movement of the plunger 61 is utilized to rock a lever 66 about a horizontal plane so as to swing the shoe 67 and thereby shift the gear unit d^s . This construction is in all respects identical with that fully related and described in our co-pending application, Serial #850175, filed July 10th, 1914, and therefore need not here be elaborated. It will be noted that this construction brings the lever D into the position of utmost convenience as above described and it may also be noted that the lever U is enabled to operate the sleeve 10 and the motion-reverser J by mechanism and connections identical with that also fully detailed in the said co-pending case and which therefore need not here be re-elaborated.

Having thus revealed this invention, we claim as new and desire to secure by Letters Patent of the United States:

1. A machine-tool combining a spindle; a table positioned thereunder adapted to translate transversely to said spindle; frame-units for mounting said spindle and table in said relation, and providing a relative adjustment between said table and spindle in a direction parallel with the axis of the spindle and also enabling the vertical distance between said spindle and said table to be adjusted; speed means for rotating said spindle at a pre-determined rate, a feed change mechanism carried by one of said frame-units and located below said table, and having its gear shift lever accessible from the forward side of said table; a first transmission deriving from said spindle motion at a rate directly proportional to the

speed of the spindle and extending through said feed-change mechanism into propelling relation with said table; a second transmission deriving motion independently of said spindle and adapted to be brought into propelling relation with said table independently of said feed-change mechanism to effect a quick-traverse thereof; and a shifting means for rendering the one or the other of said transmission effective to propel said table.

3. A milling-machine organization combining a column; a spindle; a stepped pulley adapted to rotate said spindle; a secondary pulley journaled at the side of the column and adapted to be actuated by a belt independently of said spindle; a knee; a saddle; a table supported below the spindle; a propelling mechanism mounted on one of said parts; a pair of independently movable extensible shafts extending at one side of said column from said mechanism, one of said shafts being connected to said independent pulley, and means operatively connecting said other shaft to said spindle independently of said auxiliary pulley.

4. A machine-tool organization combining a spindle; a variable-speed means for rotating said spindle; a table; a feed-change mechanism; a motion-reverser intervening between said table and said feed-change mechanism; a transmission adapted to connect said spindle, said feed-change mechanism, said motion-reverser and said table together in series in said sequence; another transmission deriving motion independently of said spindle and adapted to be brought into propelling relation with said table independently of said feed-change mechanism to execute a quick-traverse thereof; a shifting means adapted to render said second transmission inoperative to impart a quick-traverse to said table and to render said first transmission operative to cause said table to feed at a rate determined both by said spindle and by said feed-change mechanism.

5. A machine-tool organization combining two actuated elements, the one being a table and the other being a spindle; a first and a second frame-unit, one of said frame-units supporting the spindle and the other

supporting the table; an intermediate frame-unit having a vertically adjustable connection with the first frame-unit and 55 also having a horizontally adjustable connection with the second frame-unit, one of said frame-units and also the weight of one of said actuated elements being both supported by another of said frame-units; an 60 organized feed-change mechanism carried by one of the movable frame-units and geared to actuate the adjacent frame-unit and also providing a hand-operative part located adjacent said last-mentioned element; a first transmission connecting said feed-change mechanism with said spindle whereby said table may be propelled at a rate determined mutually by said spindle 65 and said feed-change mechanism; and another interchangeably available transmission deriving motion independently of said spindle and adapted to propel said table at a quick-traverse rate independently of said feed-change mechanism. 70

6. A machine-tool organization combining a spindle; means for rotating said spindle at a variable rate; a table; a feed-change mechanism and a motion-reverser between 80 the table and the spindle; a first transmission connecting said spindle and said table through said feed-change transmission and said motion-reverser; a second transmission deriving motion independently of said spindle and connected to said first transmission 85 between said motion reverser and said feed-change mechanism and shunting said feed-change mechanism to impart a quick-traverse to said table at a rate independent of said feed-change mechanism; a shifting 90 means adapted to disconnect said second transmission and to establish a mechanical connection between said spindle and said table through said first transmission whereby it may cause said table to feed at a rate 95 determined by said feed-change mechanism.

In witness whereof, we hereunto subscribe our names as attested by the two subscribing witnesses.
